APPARATUS FOR CUTTING DIES

Stanley Leskiewicz, Lynn, Mass., assignor to North Shore Cutting Die Company, Lynn, Mass.

Substituted for abandoned application Serial No. 332,715, May 1, 1940. This application May 22, 1941, Serial No. 394,732

2 Claims. (Cl. 153—48)

The present invention relates to a clamp and in particular to a clamp of the type used in connection with the forming of cutting dies for shoes and the like and is a substitution for my earlier application Serial No. 332,715, filed May 1, 1940.

In my earlier application Serial No. 149,177, which has issued as Patent No. 2,195,537, there is shown a clamp of this type by means of which the cutting or clicker die is formed to the shape of a template to which the die is to be cut out. In this clamp the template is cut or slotted at its edge in the place where the projecting arm from the base of the clamp fits in the edge of the template. While this construction is for the most part satisfactory, sometimes it is not desirable to notch or slot the template and in such cases the clamp of the type described in the present invention is more useful.

The type of clamps described in the present invention and that of my copending application mentioned above are specifically used for forming dies to templates and in this connection it will be noted that the template is clamped in a horizontal position and the die element in a vertical position at the edges of the template. Further, in the present type of clamp, the template must be accurately held to the cutting die, and yet the clamp for this purpose must be sufficiently small so as not to interfere with the operator in forming the die with the forming machine. The clamps therefore of the present invention have these distinct purposes and special uses over other clamps for other types of work.

Further advantages and merits of the present invention will be more fully explained and understood from the specification below illustrating an embodiment of the invention in connection with the drawing, in which:

Figure 1 shows an elevation of the clamp with the template in section.

Figure 2 shows the clamp in elevation with one portion thereof in section.

Figure 3 shows a plan view of the invention as viewed from the top of Figure 1, and,

Figure 4 shows an exploded perspective view with parts in the approximate position in which they are assembled.

Referring to the figures in which the same elements are indicated by the same numbers, the clamp comprises, a base plate 1, and angle plate 2, and a top clamping screw 3. The base plate 1 is provided with two clamping surfaces 4, the top horizontal clamping surface as viewed in Figure 1, and 5, the side vertical surface as viewed in Figure 1. The central portion of the plate 1

may be hollowed away as indicated at 6. The base clamp plate 4 has projecting from its top surface a bar 7, which bar projects from a place in the clamping surface somewhat removed from the edge 5, but preferably nearer the edge 5 than the other unused face 8 of the clamp. This projecting bar 7 projects through a slot 9 in the angle plate 2 and is pinned in the angle plate 2 by means of the rod 10 which passes transversely through the wall of the angle 2 and the bar 7. The arm 7 is pinned in such a way as to allow the base clamp plate 1 to pivot freely to the angle plate 2. The angle plate 2 has two arms, one, 11, the horizontal arm as shown in Figure 1 in which the arm 7 is pivoted, and 12, the vertical arm which extends opposite to the face 5.

It will be noted in Figure 4 that the template 14 is provided with a slot 15. This slot is of the same shape and size as the bar 7 and when the clamp is assembled for use the bar is put through the slot 15 and into the slot 9 in the arm 11 of the clamp 2. The pin 10 which may be pushed backwards so as to allow the passage of the bar 7 into the slot 9, is now pushed forward again passing through the hole 16 in the bar 7 which is aligned with the hole 17 in the arm 11, and by means of which the plate 1 is supported freely to the arm 11 of the angle plate 2. The pin at one face of the arm 2 is provided with a supporting bracket 13 from which there extends a second pin element 18. This pin element 18 when in place passes through the hole 19 in the plate 11 at or near the corner of the arm 12. This whole assembly of the pin 10, the bracket 13 and the pin 18 is permanently assembled in position in the bracket arm 2, so that while it may be pushed transversely back and forth in the arm 11, it will remain located in the holes 17 and 19 by virtue of the enlarged head 20 at the end of the pin 18. When the head 20 is pushed against the arm 11, the end of the pin 10 is clear of the slot 9 so that in that position the base clamp 1 with the bar 7 may be disassembled from the top clamp plate 2. This construction permits the template 14 to be removed from the clamp and a new template inserted. Each template 14, before it is used with the clamp, is pierced with the slot 15 which is removed from the edge 21 of the material of the template so that the edge of the template is smooth and continuous. The horizontal surface of the base plate 4 is used to clamp the template, while the vertical surface 5 is used to clamp the die strip 22. When the device is assembled for use, the template 14 which has already been pierced with the slot 15 is put in

place between the clamping surface 4 and the top clamping arm 11 through which the screw 3 passes holding the template 14 against the clamping surface 4. Before the screw 3 is tightened, the die strip 22 is put in place along the edge of the template and the whole assembly with the template and the die strip is held together by means of the clamping screw 3. The template 14 may be provided with a number of slots 15 near its edge in the position indicated in Figure 4, and the position of the clamp may be changed if the template is very large or if it has a great number of sharp bends. In many cases however the die strip can be formed to the template without changing the position of the clamping plate 15 during the operation.

Having now described my invention, I claim:

1. A clamp for forming a die strip to a template form, comprising two clamping elements of which one is an L shaped clamping head, providing pairs of opposed clamping surfaces positioned substantially at right angles to each other, one of said clamping elements having a bar member projecting from one of its surfaces, the bar being located in spaced relationship to the edge of said surface and extending into a slot in the other of said elements and means pivoting said bar in said slot comprising an adjustable U shaped connecting member having its side element extending in apertures in said L shaped clamping head, said 30

5 apertures being substantially parallel to said clamping surfaces with one side of the U shaped elements extending through said slot and said bar and the other at the junction of the arms of the L shaped clamping head, said U shaped element being adjustably mounted so that it can be withdrawn from said slot to permit the elements to be separated one from the other.

10 2. A clamp for forming a die strip to a template form, having a perforation therethrough, comprising a base element and an angle element, having an arm with a slot therein, a bar projecting from one surface of the base element, said bar being located in spaced relationship to the edges of said surface and extending through the perforation in the template and into the slot in said arm of the angle element, and means pivoting the bar in the arm of said angle element comprising an adjustable U shaped and pivoting member having its side element extending in apertures in said angle elements with one side of said U shaped element extending through said slot and said bar and the other side extending through said angle element near the junction of the angle, said U shaped element being adjustably mounted so that it can be withdrawn from said slot to permit the elements to be separated one from the other.

25 STANLEY LESKIEWICZ.
